ADVERTISING MECHANISM

Fred H. Jensen, Grand Rapids, Mich.

Application August 10, 1935, Serial No. 35,576

2 Claims. (Cl. 40—126)

The present invention relates to advertising mechanisms; and its object is, generally, to provide an improved mechanism of that character which shall attract attention and suggest advantages of goods offered for sale; and particularly, to provide such a mechanism in which simulations of destructive insects are displayed in motion.

This and any other and more specific objects 10 hereinafter appearing are attained by, and the invention finds preferable embodiment in, the illustrative mechanism and devices particularly described in the body of this specification and illustrated by the accompanying drawing, in 15 which:

Figure 1 is a view in perspective of an advertising mechanism, its top layer being partially broken away;

Figure 2 is a horizontal sectional view thereof 20 taken on line 2—2 of Figure 3;

Figure 3 is a vertical sectional view of the same taken on line 3—3 of Figure 2;

Figure 4 is a detail vertical sectional (enlarged) view of parts of the same taken on the 25 same line 3—3.

In the embodiment of the invention illustrated by the drawing, my advertising mechanism includes a box base 1 with a horizontal platform or cover plate having a narrow circuitous track gap 3 therethrough dividing the cover plate into two sections, the outer section 4 being supported on the upper edges of the sides 5 of the box and held against sliding movement thereon by the pins 6 extending upwardly 30 from said sides and engaging in sockets 7 in the under side of said section, and the middle section 8 resting on suitable supports in the box, as the pins 9 whose upper ends are received in sockets 10 in the under side of said 35 middle section, so that these sections 4, 8 are removably held in a position maintaining the track gap of proper width throughout. A plurality of pulleys 11 in the box are rotatable on these pins 9 and carry a belt 12 which is travelled by suitable means as by the motor 13 whose shaft pulley 14 and a pulley 15 on one of said pulleys 11 carry the driving belt 16 as 40 illustrated.

Devices 17 simulating winged moth insects or 45 the like as shown which destroy furs, woolen fabrics, etc. are carried above the cover plate by the belt 12 underneath. These devices have downwardly extending members, the supporting member 18 whose lower end is fastened on the belt and the members 21 which simulate the insect's legs. These devices are flexibly supported so as to be vibratile, the belt 12 itself

being, of course, flexible between its carrying pulleys and the member 18 being a slender spring wire, and the leg members 21 and also the wing simulating parts 22 are flexible and elastic.

As the belt is travelled carrying these devices with it, the resistance of the air through which they pass flexes the member 18 and causes the devices to vibrate somewhat; and this vibration is increased and such simulation is augmented by the frictional contact of some or all of said members with the stationary top cover or the top layer 19 thereof which has upwardly extending brush fibres or bristles 20 through which the legs 21 pass and the support member 18 also passes, these fibres at the sides of the track gap extending over the same as best shown in Figure 4.

It will be seen that these devices and their various parts are thus caused to vibrate or 20 flutter by the traveling belt, so that a moth in its flight is suggested and simulated thereby.

To heighten the effect of this advertising mechanism, an article of fur, woolen fabric or the like, may be laid on the cover plate or disposed around the structure.

The invention being intended to be pointed out in the claims, is not to be limited to or by details of construction or arrangement of the embodiment thereof illustrated by the drawing 30 or hereinbefore described.

I claim:

1. In mechanism of the character described: a platform having outwardly extending flexible bristles; a belt beneath the platform movable in a direction parallel therewith; devices above the platform having downwardly extending members, some of said members being fastened on the belt for circuitously traveling the devices by the belt and some of said members 35 being vibratile and frictionally engaging the bristles in the movement of the belt to vibrate the devices.

2. In mechanism of the character described: a platform having a circuitous track gap therethrough and outwardly extending bristles; a belt beneath the platform movable in a direction parallel with the gap; devices above the platform having downwardly extending members, some of said members being fastened on the belt for circuitously traveling the devices by the belt and some of said members being vibratile and frictionally engaging the bristles adjacent the gap in the movement of the belt 45 to vibrate the devices.

FRED H. JENSEN.
